ADJUSTABLE AND DISASSEMBLABLE REEL

Domenico C. Frate, Baltimore, and Daniel G. Stetka, Towson, Md., assignors to Western Electric Company, Incorporated, New York, N.Y., a corporation of New York

Application July 8, 1957, Serial No. 670,571

2 Claims. (Cl. 242—118.5)

This invention relates to an adjustable and disassemblable reel, and more particularly to an adjustable reel upon which strand material, such as cable, may be wound, the reel being disassemblable to permit withdrawal of wound cable.

In the manufacture of cable, it is sometimes desired to cut and coil relatively short lengths of cable to which terminal blocks may be secured. The required lengths of such cable to be cut and coiled vary; therefore, it has been found desirable to provide an adjustable reel upon which cable might be coiled in order to obtain a predetermined number of coil layers in the coiled cable, the number of layers being independent, within limits, of cable length. In addition, it is desirable to provide a disassemblable reel so that the coiled cable may be secured, as desired, and then removed intact from the reel.

An object, therefore, of the invention is to provide an adjustable and disassemblable reel.

Another object of the invention is to provide an adjustable reel upon which strand material, such as cable, may be wound, the reel being disassemblable after winding to permit withdrawal of the wound cable.

An adjustable and disassemblable reel embodying certain features of the invention, may include a drum having a fixed flange secured thereto. The drum is formed with a plurality of spaced longitudinal grooves and a plurality of circumferential slots extending from each of the grooves. A detachable flange is provided having an aperture therein to permit the detachable flange to be placed on the drum and to be movable therewith. A plurality of lugs extending from the detachable flange are provided, whereby the lugs enter the grooves in the drum and the slots extending from the grooves to position the detachable flange on the drum at a preselected distance from the fixed flange. At least one threaded stop member is provided, designed for reception in a desired one of a plurality of tapped apertures formed in the bottoms of the grooves. The tapped apertures are so located that a stop member received therein will engage one of the lugs and stop the advancement of the detachable flange at a point where the lugs are aligned with preselected ones of the circumferential slots, in order to position the detachable flange parallel to and at a preselected distance from the fixed flange. Preferably, the slots extend at an angle of between one and five degrees toward the fixed flange.

Other objects and advantages of the invention will appear from the following detailed description of a specific embodiment thereof, when read in conjunction with the appended drawings, in which:

Fig. 1 is a front elevation of an adjustable and disassemblable reel forming an embodiment of the invention and showing the parts assembled, and

Fig. 2 is a vertical section taken along line 2—2 of Fig. 1.

Referring now in detail to the drawings, the adjustable and disassemblable reel comprises a fixed flange 10,

which is secured, such as by welding, to a generally cylindrical drum 11, upon which strand material, such as cable, may be wound. The drum 11 is preferably tubular, as shown in the drawings. The outer periphery of the drum 11 is preferably tapered slightly, the larger end being adjacent to the fixed flange 10, as shown in Fig. 1. Satisfactory results have been obtained with a taper of from one to five degrees. The purpose of the taper is to facilitate withdrawal of a coil, when it is desired to pull the coil longitudinally off of the drum 11.

The outer periphery of the drum 11 is provided with a plurality of spaced, longitudinally extending grooves 12—12. The longitudinal grooves 12—12 extend from the end of the drum 11 remote from the fixed flange 10, in a direction parallel to the longitudinal axis of the drum 11, to a point near the fixed flange 10. The grooves extend only part way through the thickness of the drum 11, as best seen in Fig. 2. In the preferred example shown in the drawings, there are three grooves provided, which are spaced approximately 120° apart.

Each of the grooves 12—12 is provided with a plurality of short slots 13—13 connecting therewith and extending therefrom for a short distance along the circumference of the drum 11. The slots 13—13 are disposed, one slot 13 for each of the grooves 12—12, in a plurality of planes substantially parallel to the fixed flange 10 but spaced at preselected distances therefrom, one slot 13 being provided for each of the grooves 12—12 in each plane and all of the slots 13—13 in any one plane extending in the same circumferential direction from the grooves 12—12. In the example illustrated in Fig. 2, all of the slots 13—13 extend in a counter-clockwise direction from the longitudinal grooves 12—12 and there are seven such planes with three slots in each plane. It is preferred that the slots 12—12 extend at a slight angle toward the fixed flange 10.

An adjustable and detachable flange 14 is provided having a central aperture 16 therethrough. The aperture 16 is of such diameter as to permit the detachable flange 14 to be placed over the end of the drum 11 remote from the fixed flange 10 and, also, to permit the detachable flange 14 to be moved longitudinally with respect to the drum 11 toward the fixed flange 10, to a point at least as close thereto as the plane of the slots 13—13 closest to said fixed flange 10.

The detachable flange 14 is provided with a plurality of lugs 17—17, equal in number and spaced from each other in accordance with the number and spacing of the grooves 12—12, so as to be capable of alignment therewith. The lugs 17—17 extend radially inwardly for a predesigned distance, such that a slight clearance will exist between them and the inner edges of both the grooves 12—12 and the slots 13—13. The lugs 17—17 are formed of such size as to be capable of entering the longitudinal grooves 12—12 and sliding longitudinally therewithin and, in addition, entering and sliding circumferentially within the slots 13—13. In the preferred example, as best seen in Fig. 2, there are provided three such lugs 17—17 spaced approximately 120° apart, so as to be capable of alignment with the grooves 12—12 of the drum 11, which are spaced similarly.

It is preferred to provide stop means for the detachable flange 14, positionable adjacent to each plane of the transverse slots 13—13. A preferred example of such stop means is shown in the drawings to comprise a plurality of headed threaded members 19—19, which are designed to be screwed within any of a plurality of tapped apertures 20—20 formed in the drum 11 and extending radially inwardly from the bottoms of the longitudinal grooves 12—12. The tapped apertures

20—20 are so located that, when the threaded members 19—19 are screwed therein, the right-hand portions of the heads of the threaded members 19—19, as seen in Fig. 1, are approximately in line with the left sides of the corresponding transverse slots 13—13. The right-hand portions of the heads of the threaded members 19—19 are intended to stop the lugs 17—17 from further longitudinal movement to the left, as seen in Fig. 1, at a position in alignment with the slots 13—13, so that the lugs are in position to enter the slots 13—13 upon counterclockwise rotation of the detachable flange 14, as viewed in Fig. 2. The threaded members 19—19 should be of such height that they will not extend above the top of the longitudinal grooves 12—12, thereby preventing engagement with strand material wound on the drum 11.

Assembly and operation

To assemble and operate the adjustable and disassemblable reel, the detachable flange 14 is placed parallel to the fixed flange 10 and somewhat to the right of the drum 11, as viewed in Fig. 1. The detachable flange 14 is rotated until the lugs 17—17 are in alignment with the longitudinal grooves 12—12. The detachable flange 14 is then moved to the left, as viewed in Fig. 1, until the lugs 17—17 are in alignment with the slots 13—13 in the particular plane desired. This alignment is automatic when stop means, such as the threaded members 19—19, are provided.

The detachable flange 14 is then rotated counterclockwise, as viewed in Fig. 2, until the lugs 17—17 are in contact with the closed ends of the slots 13—13 remote from the grooves 12—12. In the example shown in Fig. 1, the detachable flange 14 is located at the outermost plane provided, but it can be readily seen that the detachable flange 14 could be positioned similarly in any of the other six planes of slots 13—13, shown in Fig. 1. If the reel is set up so that, when operated, rotation of the drum 11 is in a clockwise direction, as seen in Fig. 2, the lugs 17—17 will tend to remain at the outer ends of the slots 13—13, and no external securing means are necessary. It would, however, be possible to use external means (not shown) to positively lock the detachable flange 14 in place.

The assembled reel, having the detachable flange 14 positioned for the desired drum length, is now ready for use, for example, as a cable take-up reel. The cable is wound by conventional means (not shown) around the outer periphery of the drum 11 and between the two flanges 10 and 14. When the desired amount of cable has been wound, the winding means (not shown) are stopped and the cable is cut to length and secured, as desired. The detachable flange 14 may be removed by reversing the assembly steps, as will be obvious. Removal of the detachable flange is facilitated when the slots extend at a slight angle toward the fixed flange 10. The coiled cable may then be pulled longitudinally off

of the drum 11, particularly when the tapered drum construction is used. The reel may then be reassembled and the process repeated.

It will be manifest that this invention is not limited to the specific details described in connection with the above embodiment of the invention and that various modifications may be made without departing from the spirit and scope thereof.

What is claimed is:

1. An adjustable and disassemblable reel, which comprises: a hollow drum having a generally circular cross section; a fixed flange secured to one end of said drum, said drum being provided with a plurality of longitudinal grooves in the outer surface thereof extending from the free end thereof, a plurality of tapped apertures in the bottoms of the grooves, and a plurality of short circumferential slots extending from each of the grooves, the slots being disposed in a plurality of planes parallel to and spaced at preselected distances from said fixed flange, one slot being provided for each groove in each plane, each slot in each plane extending in the same circumferential direction from the groove associated therewith; a detachable flange having an aperture therein of greater diameter than the outer diameter of said drum; a plurality of lugs secured to said detachable flange, extending radially inward therefrom, and spaced so as to be alignable with the grooves in said drum, so that said detachable flange may be placed over the free end of said drum and advanced therealong with said lugs entering the longitudinal grooves in said drum and advancing therewith; and at least one threaded stop member designed for reception in the tapped apertures, the tapped apertures being so located that a stop member received therein will engage one of said lugs and stop the advancement of said detachable flange at a point wherein said lugs are aligned with a preselected plane of the slots, in which position said detachable flange may be rotated with respect to said drum so that said lugs enter the slots in said drum to mount said detachable flange in place parallel to said fixed flange and spaced at a preselected distance therefrom.
2. An adjustable and disassemblable reel according to claim 1, wherein the slots extend at an angle of not less than one degree and not more than five degrees toward said fixed flange.
